UNITED STATES PATENT OFFICE.

LYMAN C. ROGERS, OF MANCELONA, MICHIGAN.

FLUE-CLEANER.

No. 894,857.

Specification of Letters Patent.

Patented Aug. 4, 1908.

Application filed March 12, 1907. Serial No. 362,037.

To all whom it may concern:

Be it known that I, LYMAN C. ROGERS, a citizen of the United States of America, residing at Mancelona, in the county of Antrim and State of Michigan, have invented new and useful Improvements in Flue-Cleaners, of which the following is a specification.

This invention relates to flue cleaners, and one of the principal objects of the same is to provide a flue cleaner in which the cleaning head may be readily attached and detached to and from the handle, and in which interchangeable heads may be readily connected to the handle.

Another object of the invention is to provide a flue cleaner with a head provided with a peripheral groove for the attachment of the cleaning element, and providing means whereby the heads may be quickly attached to the handle of the cleaner.

These and other objects may be attained by means of the construction illustrated in the accompanying drawings, in which:

Figure 1 is a plan view of one of the flue cleaner heads, a portion of the same being broken away to illustrate the manner of securing the cleaning element in said head. Fig. 2 is a transverse sectional view of the cleaner head and showing the manner of securing the head to the handle bar. Fig. 3 is a view similar to Fig. 1, showing a different form of cleaning element secured to the head. Fig. 4 is a transverse sectional view of the head shown in Fig. 3.

Referring to the drawing for a more particular description of my invention, the numerals 1 designate the two members of the flue cleaning head which are secured together by means of rivets 2 or other similar fastening means. Formed in the periphery of the members 1 is a groove or recess 3, said groove

being of sufficient depth to provide oppositely disposed side clamping members 4.

As shown in Figs. 1 and 2 a series of wire coils 5 formed from a continuous strand of wire are secured in the head by means of a holding wire 6 passed through the coils and drawn tightly in the groove 3 between the head members 1, the wire coils being compressed by means of the members 4.

A ring 7 of felt, rubber, leather, or other suitable material, may be secured in the groove 3 between the head members 1, as shown in Figs. 3 and 4. The handle 8 of the cleaner is provided with a threaded end 9 and fitted on said threaded end is a nut 10. The threaded portion 9 is passed through the head members 1 and a lock nut 11 is applied to the threaded end to hold the head in place.

From the foregoing it will be obvious that in cleaning a flue or chimney the head shown in Figs. 1 and 2 may be quickly removed and replaced by another such as shown in Figs. 3 and 4, merely by the removal of the nut 11.

My invention is of simple construction, and has been found very efficient in cleaning chimneys and flues.

Having thus described the invention, what I claim is:

A flue cleaner comprising a head composed of two members secured together and provided with a peripheral groove and oppositely disposed clamping members, and a continuous series of wire coils secured in said groove by a holding wire passing through all of said coils, substantially as described.

In testimony whereof, I affix my signature in presence of two witnesses.

LYMAN C. ROGERS.
